UNITED STATES PATENT OFFICE.

LENA GOULD, OF ROCHESTER, INDIANA.

DESIGN FOR A DOLL.

46,637.

Specification for Design.

Patented Nov. 10, 1914.

Application filed September 29, 1914. Serial No. 864,167. Term of patent 7 years.

To all whom it may concern:

Be it known that I, LENA GOULD, a citizen of the United States, residing at Rochester, in the county of Fulton and State of Indiana, have invented a new, original, and ornamental Design for Dolls, of which the following is a specification, reference being had to the accompanying drawing, forming part thereof.

Figure 1 is a front elevation of the doll, showing my new design. Fig. 2 is a side elevation of the doll, showing my new design.

I claim:

The ornamental design for a doll, as shown.

LENA GOULD.

Witnesses:

FRANCES E. ANDERSEN,
EDWARD E. MURPHY.
